Patented Oct. 28, 1913.

UNITED STATES PATENT OFFICE.

CHARLES H. LUCAS, OF WALTHAM, MASSACHUSETTS.

PAPER-GAGE.

1,076,682.

Specification of Letters Patent. Patented Oct. 28, 1913.

Application filed December 5, 1911. Serial No. 664,121.

To all whom it may concern:

Be it known that I, CHARLES H. LUCAS, a citizen of the United States, and a resident of Waltham, in the county of Middlesex and State of Massachusetts, have invented certain new and useful Improvements in Paper-Gages, of which the following is a specification.

This invention relates to devices for measuring, especially the thickness of material, and the invention is designed particularly for measuring the thickness of paper.

One of the objects of the invention is to provide a device of this character which may be readily carried in the pocket and which is dust proof.

Another object of the invention is to provide a gage having two coöperating measuring members, the opposing faces of which are so formed that they will not press or sink into material such as paper, in order that the thickness may be accurately gaged.

Another object is to provide a gage having multiplying gearing which is constructed so that there will be no lost motion or "back-lash" in said gearing.

To these ends the invention consists in the construction and combination of parts substantially as hereinafter described and claimed.

Of the accompanying drawings,—Figure 1 is a front elevation or face view of the gage drawn to substantially full size. Fig. 2 is an enlarged rear view of the same with the back-plate removed. Fig. 3 is a view similar to Fig. 2 but showing some of the parts broken out and others in section. Fig. 4 represents a section on line 4—4 of Fig. 2 and including a back plate.

Similar reference characters indicate the same or similar parts in all of the views.

The case 10, preferably circular in form, is provided with an internal annular flange 11 for the dial plate 12. It is also provided with a tight fitting bezel 13 carrying the crystal 14. Near the rear edge of the casing is another annular internal flange 15, against which the back plate 16 is confined by suitable means such as screws. The case is also formed or provided with bearings 17 for the longitudinally movable gaging bar or slide 18 having a finger piece or push piece 19 at one end. The slide 18 passes through a sleeve extension 20 of one of the bearings 17, and secured on said sleeve as by a screw 21, is a fixed jaw 22 having a flat face 23. The

movable measuring member to coöperate with the jaw 22 comprises a jaw 24 having a flat face 25, said jaw being secured to the reduced end 26 of the slide 18 by suitable means such as a screw 27. The flat faces 23, 25 are sufficiently wide to avoid becoming embedded in material such as paper inserted between the jaws, under the action of the spring or springs presently described. 60 If a screw or other positive means were employed to close the jaws upon the material to be measured, such extra pressure might be accidentally exerted as would prevent the jaws from accurately indicating the thickness. Moreover, as will be presently understood, the operation of measuring or gaging is effected much more quickly than if screw mechanism were employed for closing the jaws. A pin 28 projects laterally from the 65 slide 18 and engages a guide 29, to prevent the slide from rotating. As shown by comparing Figs. 2 and 3, said guide consists of two ribs between which the end of the pin 28 extends, said ribs being preferably integral with a block 30 that is secured inside the case by screws 31. A spring 32 connects the pin 28 with an anchor 33 suitably secured in the case. 70

A staff or arbor 34 carrying a pointer 35 to coöperate with the markings on the dial plate 12 is supported by said dial plate and by a bridge 36. A small pinion 37 carried by said staff or arbor meshes with a larger pinion 38 carried by a barrel 39 which is mounted in the dial plate and bridge 36. A chain 40 engages the barrel 39 and is preferably coiled once around the said barrel (see Fig. 4) and it is secured to said barrel by suitable means such as a screw 41 entering the barrel and having its head extending over and clamping the chain. Said chain extends in two directions from the barrel. At one end it carries an eye 42 which is secured, as by means of a screw, to a pin 43 projecting from the slide 18. At the other end, the chain is connected by a coupling 44 with one end of a spring 45 the other end of said spring being connected by an anchor 46 to the case. A coiled hair spring 47 is 80 connected at one end to the staff or arbor 34 and at the other end to the bridge 36. 85

It will be readily understood from Figs. 2 and 3 that the spring 45 exerts tension in such direction as to aid the spring 32 in holding the gage bar or slide 18 in the normal or closed position shown in said figure, 90 95 100 105 110

and of course to also hold the jaws closed upon material inserted between them. When the gaging slide is operated in a direction to open the gage such movement extends 5 both springs 32 and 45 and through the chain member 40 of the gearing rotates the barrel 39 and the intermeshing pinions 38, 37 causes the staff or arbor 34 to rotate so that the pointer 35 will indicate on the dial 10 the space existing between the flat faces of the two jaws.

The construction illustrated shows in practice that variations of thickness of material between the jaws may be accurately 15 gaged or indicated in fractions of 1/1000 of an inch, without fluctuations due to any lost motion or back-lashing between members of the gearing. The spring 45 not only aids the spring 32 in closing the jaws, but also 20 causes the barrel 39 to accurately follow the slightest movements of the gaging slide, and to remain in the position to which it is rotated. The spring 47 is coiled in a direction to be wound up when the jaws are 25 opened and therefore this spring 47 also exerts what slight force it has in the same direction as the springs 32 and 45, and also serves to prevent any lost motion or back-lash between the pinions 37, 38. In other 30 words, the spring 47 when unwinding, tends to rotate the staff or arbor 34 in the direction of the arrow in Fig. 3, and the spring 45 when collapsing or shortening tends to rotate the barrel 39 and pinion 38 in the 35 direction of the arrow in the same figure and such direction of movement is the same as that imparted by the spring 32 in closing of the jaws. Therefore all springs act in the same direction to close the jaws, and 40 when there is no material between the jaws, the pointer will accurately indicate zero on the dial.

It will be seen that the device or implement is exceedingly simple, is compact and 45 dust proof so that it may be carried in the pocket, with no structure of jaws which would be likely to become caught in the lining of the pocket, and having intermediate connections between the slide or actuator 18 50 and the indicator that are not liable to the errors which usually occur with ordinary multiplying gearing.

I claim:—

1. A gage having a fixed jaw, a slide carrying another jaw to coöperate therewith, 55 two intermeshing pinions, a pointer actuated by one pinion, connections between the other pinion and the slide for rotating the former from the latter, and three independent 60 springs individually connected to the two pinions and the slide to actuate them in one direction.

2. A gage having a fixed jaw, a slide carrying another jaw to coöperate therewith, two intermeshing pinions, a pointer actuated by one pinion, a chain connected to the slide and to the other pinion whereby a movement of the slide in one direction is transmitted to said pinion, and three independent springs one connected to the slide, another to 65 the chain, and the third to the pinion having the pointer, said springs being connected to act to close the jaws.

3. A gage having a fixed jaw, a slide having a jaw to coöperate therewith, said slide 75 having two pins, a spring connecting one of said pins to a fixed point, two intermeshing pinions, a pointer actuated by one pinion, a chain for transmitting motion from the slide to one of said pinions, a spring connecting said chain with a fixed point, and an independent spring connected to the pinion carrying the pointer, said springs being connected to act to close the jaws.

4. A gage having two coöperating members, a slide carrying one of said members, a dial, a pointer arbor having a pinion, a barrel having a pinion meshing with the pinion of said arbor, a chain connected to said barrel and to said slide, a spring for 90 holding the slide in normal position, and a spring connected to said chain to exert a tension thereon in a direction to supplement the action of the first mentioned spring.

5. A gage having two coöperating measuring members, a slide carrying one of said members, two intermeshing pinions, a pointer actuated by one pinion, a chain connecting the slide with one of said pinions for actuating it in one direction, and three independent springs for the two pinions and the slide, all of said springs acting in one direction to close the measuring members.

6. A gage having a slide, two jaws, one of which is carried by said slide, a spring 105 for actuating the slide in one direction, a barrel having a pinion, a chain coiled around said barrel and attached thereto and having one end connected to the slide, a spring connected to the other end of said chain, a dial, 110 a pointer coöperating with said dial, an arbor for said pointer having a pinion meshing with the pinion of said barrel, and a spring for actuating said arbor, all three of said springs acting to move the movable 115 elements to which they are connected in a direction to return the pointer to zero and close the jaws.

In testimony whereof I have affixed my signature, in presence of two witnesses.

CHARLES H. LUCAS.
